UNITED STATES PATENT OFFICE.

CHARLES R. PRATT, OF MONTCLAIR, NEW JERSEY, ASSIGNOR TO OTIS ELEVATOR COMPANY, OF JERSEY CITY, NEW JERSEY, A CORPORATION OF NEW JERSEY.

HYDRAULIC ELEVATOR.

1,156,433.

Specification of Letters Patent. Patented Oct. 12, 1915.

Application filed March 10, 1913. Serial No. 753,180.

To all whom it may concern:

Be it known that I, CHARLES R. PRATT, a citizen of the United States, residing in Montclair, in the county of Essex and State of New Jersey, have invented a new and useful Improvement in Hydraulic Elevators, of which the following is a specification.

My invention relates to elevators or other hoisting apparatus and comprises novel and improved apparatus and means for controlling the same, so as to provide a simple, practical and efficient system of power transmission wherein power for the hoist is derived from a prime mover or motor and transmitted under varying speed conditions to a driven member forming a traction or hoisting element in an elevator system.

The invention is applicable to the transmission of power in general, and elevators or hoists in particular, and is especially adapted to an elevator operated by the power delivered by an alternating current motor.

Owing to the general usage of electricity for power purposes throughout the civilized world, and since a large proportion of this is alternating current, it is but natural that alternating current motors be extensively employed for driving elevators. Since it is a characteristic of such motors to require an enormous current in starting under load, it becomes of great advantage to allow the motor to operate at substantially constant speed in one direction and to interpose some form of variable speed power transmission between the motor and the load, and to effect the control of the load by controlling the said power transmission.

In carrying out the invention, I propose to employ a power transmission embodying a number of novel features having great practical value, combined with a system of automatic control adapted best to effect the most satisfactory results.

Figure 1 of the drawings shows a traction elevator system containing an embodiment of my invention; Fig. 2 is a wiring diagram for the pilot motor shown at the left hand end of Fig. 1; Fig. 3 is a sectional view of the differential gearing between the pilot motor and the traction sheave or driven member; Fig. 4 illustrates, in part section, a multiple piston variable stroke pump and the method of controlling its stroke; Fig. 5 is a sectional view of an improved pump.

Like reference characters denote similar parts in all of the figures.

Referring to Fig. 1, an alternating current electric motor is designated by the numeral 36, and the same is connected through a main line switch to a suitable source of alternating current supply designated by the characters *a*, *b* and *c*. The motor 36 operates at substantially constant speed and always runs in one direction. A small direct current generator 100 is connected to run with the motor 36 and furnishes a constant potential supply of direct current used in connection with the pilot motor 51, as hereinafter described. The power transmission mechanism comprises a pump 37 which is directly connected or coupled to the motor 36 and a fluid pressure engine 38 which may be of any desired type of fluid pressure motor, but is preferably of that type illustrated herewith and known as the "Brotherhood" engine. The same is operated by fluid pressure from the pump 37, through suitable pipe connections such as the pipes 39 and 40, and is connected to drive a driving element or traction sheave 41. The sheave 41 is connected by any suitable means such as the intermeshing gears 52 and 88, to a differential gear 50. The latter being also connected through the gears 85 and 86 with a pilot motor 51 equipped with the conventional spring pressed electrically released brake 76. An elevator car 42 is suspended from a plurality of cables such as 43 which are wrapped about the traction sheave 41 and an idler sheave 44 one or more turns, as desired, and connected at their opposite ends to a counterbalance weight 45. The differential gearing 50 is operatively connected by a cable or cables 49 to a sheave 48 associated with and operable to control the stroke and output of the pump 37.

The wiring diagram shown in Fig. 2 comprises a system of controlling circuits for the pilot motor 51, and the source of current supply designated by the usual characters + and - is derived from the direct current generator 100 through the circuit controlling switch 104 of Fig. 1. The pilot motor 51 may be of any desired type such as a shunt, series, or compound wound motor, and is here shown as a series wound motor with series field 66. The switch 53 of Fig. 2 is arranged to effect the starting, stopping, and speed control of the pilot motor, and the same comprises a number of stationary contacts such as 54, which are connected to the various sections 56, 57 and 58 of a sec-

tional speed controlling resistance. Other stationary contacts such as 64, 63, etc., are connected by conductors to the motor armature, field and brake. A pivoted switch lever comprising the sections 55 and 70, insulated from each other, is adapted to co-act with the stationary contacts above mentioned to effect the desired operation of the pilot motor. If the switch lever be moved in a right hand direction, for example, until the switch section 70 electrically engages the contacts 63 and 64, and the section 55 engages the contacts 75, 72, and 54, the pilot motor circuit is closed and the brake lifted, and the motor will operate in a predetermined direction. The pilot motor circuits may be traced from the generator 100, through switch 104 of Fig. 1, conductor +, series field 66, wire 65, contact 64, contact 63, wire 62, wire 61, through the pilot motor armature 80, wire 60, sections 58, 57 and 56 of the resistance, contact 72, and by the — main to the generator 100 of Fig. 1. The brake circuit is simultaneously completed across the + and — mains at the contact 75. The pilot motor now starts at slow speed. As the switch lever is further moved to the right, the sections 56, 57 and 58 are successively cut out of the motor circuit attended by a further increase in motor speed. If the switch lever be centered or brought back to "off" position, the motor circuit is interrupted and the brake applied to stop the motor; while if the switch lever be moved in a left hand direction the motor armature connections will be reversed and the motor will operate in a reverse direction.

The differential gearing shown in detail in Fig. 3 comprises a shaft 77 mounted to rotate in bearings 83, 83, and having affixed to it a spur gear 88 and bevel gear 78. A bevel gear 87 similar to the gear 78 is loosely mounted on the shaft 77, and is rigidly connected by a key 84 or other suitable mechanical fastening to the spur gear 86 similarly mounted on the shaft 77. A plurality of bevel gears 90, 90, are carried upon the inner circumference of the sheave 50 and are adapted to rotate and mesh with the adjacent gear teeth of the bevel gears 87 and 78. If the bevel gear 87 be operated by the pilot motor at the same speed as the bevel gear 78 is driven from the traction sheave, but in a reverse direction, it will be seen that the sheave 50 will remain stationary while the small bevel gears 90, 90, will freely rotate, each upon its own pivot. If the speed of the gear 87 varies from that of the gear 78 the sheave 50 will be rotated in the direction of the faster gear and at a speed equivalent to the differential speed of the two gears. Now, since the gear 78 is driven by the traction sheave or driven member 41, while the gear 87 is driven by the pilot motor 51 at any desired speed and direction of

rotation, the sheave 50 will effect the control and output of the pump 37 so as automatically to synchronize the speed of the pilot motor and traction sheave or driven element 41 through the cables 49 connecting the differential gear with the control sheave 48 of the pump (see Fig. 1).

Turning now to Fig. 4, I will describe the operating connection between the differential gear mechanism and the pump, showing the manner in which the pump stroke and resultant pump output is controlled and regulated. The pump shown in Fig. 4 is intended to be a diagrammatical representation of the pump shown in Fig. 5, and showing the pump stroke controlling mechanism. The axis of the latter is shown inclined with respect to the axis of rotation of the pump, and I propose to vary this angle whenever desirable so as best to accommodate the lead of the cables 49 connected thereto for different elevator installations. The pump 37 comprises a tilting head 9 whose axis may coincide with the axis of the pump shaft 1 corresponding to a neutral position or position of zero output of the pump, or whose axis may be inclined to the extent of its movement in both directions corresponding to the maximum output of the pump. The tilting head is provided with teeth 101 meshing with a worm 47 operatively connected by a shaft 102 to the sheave 48, this connection being such that a rotary movement of the sheave effects a movement of the tilting head and a resultant variation in pump stroke. I do not deem it necessary to illustrate or describe the suction and pressure chambers of the pump, and the arrangement of valve ports, since the same is well known in the art, and an example of which is found in Patent No. 1,019,521, issued to me on March 5, 1912.

The construction of the pump itself is best seen in Fig. 5, in which the shaft 1, driven from the prime mover 36, enters the port chamber or right hand end of the pump through a stuffing box 2, roller thrust bearing 3, and journal bearing 4. On the shaft 1 is pressed and keyed by a key 95, a cylinder barrel 5 in which are arranged a plurality of plungers or pistons 6, having their axis parallel to each other and to the shaft 1, and symmetrically disposed about the said shaft. The inner or left hand end of the latter is supported in and carried by a journal bearing 7 in the pump casing 8. Pivoted in trunnions 97 in the casing 8 is the tilting head 9 which carries a roller thrust bearing 10 for the rotary disk 11. In each plunger or piston 6 is a connecting rod 12 with a ball and socket bearing at one end in the plunger 6 and a similar ball and socket at the other end in the disk 11. A spherical collar 13 shown on the shaft 1, rotatable thereon and movable longitudinally thereof, is adapted

to take the radial thrust of disk 11, and, as the shaft 1, collar 13 and disk 11, all revolve together at the same speed, there will be no revolving friction between them, except that 5 caused by the angular motion of disk 11 when the tilting head 9 is placed at an operative angle to the axis of shaft 1. As the collar 13 is free to slide endwise of shaft 1, it leaves disk 11 free to seat itself in any 10 radial position on roller thrust bearing 10. This collar 13 is not essential to the proper operation of the pump as will be shown later, but its presence is desirable, as it adds to the strength of the pump and has other 15 features of practical value. The plungers 6 are of such length, and are guided at each end by bushings 14 and 15, between which is packing 16, so that they are able to transmit the torsional strain of shaft 1 by means of 20 the connecting rods 12 to the rotating disk 11. Bushings 17 in the end of each plunger 6 allow for the slight circular motion of the connecting rods 12, during each revolution, hence all of the rods 12 transmit the tor- 25 sional load at the same time with no end motion at their end contacts and they also carry the radial load of the disk 11. In order to automatically take up the slight wear occasioned by long continued use of 30 the pump and to avoid lost motion at the ball and socket bearings in the rods 12, their suction stroke spherical collars 18 and 93 are held against the balls by springs, such as 19, in the plungers and by several 35 springs 94 in each ball socket in disk 11. Cylinder barrel 5 is caused to run true with respect to its valve seat 20 by the rigidity of the shaft 1 to which it is attached by key 95 and collar 96, and is held at a film thickness 40 of fluid distance from its seat by adjusting nut 21 and roller thrust bearing 3. In order to obtain a fine adjustment of the adjusting nut 21, a differential lock nut washer 23 keyed to shaft 1 by a feather 24 and locking 45 nut 21 by pin 25, with, for example, nineteen pin holes in the part 23 and twenty pin holes in the part 21, and assuming the threaded portion of the shaft has twelve threads to the inch, gives an adjustment of 50 $1/4560$ parts of an inch to the nut 21. For safe and convenient locking of pin 25, a spring ring 26 in a groove in nut 21, snaps into a slot in pin 25, a half turn of pin 25 unlocks it for removal, and pushing it in 55 with its beveled end toward the spring, lifts the spring and allows it to snap back into the locking slot in pin 25.

Lubrication of all bearing surfaces is obtained by centrifugal circulation through a 60 hole 103 in the center of shaft 1, feeding oil first to the journal bearing 7, then through radial holes 27 in shaft 1, and collar 13 to ducts in disk 11, feeding the roller thrust bearing 10, where it is retained by centrifugal force, to the ball and socket bearings 65

and through holes lengthwise of the connecting rods 12 to the ball and socket bearings in the several plungers. The oil or lubricant also flows through the center duct 103 in the shaft 1, through radial holes 28, to the plunger bushings, and also through radial holes 29 to the end thrust and journal bearings at the right hand end of the pump. When the spherical collar 13 is not used the oil from the radial holes 27 is thrown by 75 centrifugal force into the inner groove in disk 11, and flows, as before pointed out to the roller thrust bearing 10, and ball and socket bearings of the connecting rods and associated parts. The interior of casings 8 80 and 30 can be kept free of lubricant and also free of the fluid being handled by the pump by means of separate drip pipes for each. Also to insure ample lubrication, a small oil pump and reservoir can be easily 85 arranged to maintain a substantial stream of oil flooding all bearings and other parts subject to wear. For the complete separation of the lubricant from the fluid being pumped, holes or ducts 31 discharge all the 90 oil from the plunger lubricators to one side of wall 35 and out of hole 32 in casing 8, with the balance of the lubricant; and all leakage of the fluid pumped leaking out of valve seat 20 and through the plunger 95 packing by hole 33, is held on the other side of wall 35 and discharged out of hole 34 in casing 30, either to waste or to the pump suction.

While I have illustrated and described a 100 preferred construction, and embodiment of my invention, I desire not to be limited to the precise construction and arrangement of parts herein set forth, since it is obvious that one skilled in the art could readily 105 make various changes in the apparatus disclosed without departing from the spirit and scope of the invention.

What I claim as new and desire to secure by Letters Patent of the United States is:— 110

1. In an elevator, the combination with a constantly rotating shaft, a hoisting drum or sheave, fluid power transmission mechanism operatively connecting said shaft and sheave, and electrically controlled differential mechanism for controlling said power transmission mechanism. 115

2. In an elevator the combination with a constantly rotating shaft, a hoisting drum or sheave, fluid power transmission mechanism operatively connecting said shaft and sheave, and differential mechanism connected to said drum or sheave for controlling said power transmission mechanism. 120

3. In an elevator, the combination with a 125 constantly rotating shaft, a hoisting drum or sheave, fluid power transmission mechanism arranged to transmit power from said shaft to a load carrying device associated with said drum or sheave, differential mech- 130

- anism operatively connected to said drum or sheave and to a motor, and means for controlling said motor to effect the control of the said power transmission mechanism.
5. In an elevator, the combination with a constantly rotating shaft, a hoisting drum or sheave, fluid power transmission mechanism arranged to transmit power from said shaft to a load carrying device associated with said drum or sheave, differential mechanism operatively connected to said drum or sheave and to an electric motor, and means for controlling said motor to effect the control of the said power transmission mechanism.
10. In an elevator, the combination with a constantly rotating shaft, a hoisting drum or sheave, fluid power transmission mechanism arranged to transmit power from said shaft to a load carrying device associated with said drum or sheave, differential mechanism operatively connected to said drum or sheave and to a motor, and means located on said load carrying device for controlling said motor to effect the control of the said power transmission mechanism.
15. In an elevator, the combination with a constantly rotating shaft, a hoisting drum or sheave supporting an elevator car, fluid power transmission mechanism operatively connecting said shaft and drum or sheave, a variable speed electric pilot motor controlled from said car, and means for controlling the said power transmission mechanism by the differential action of said pilot motor and power transmission mechanism.
20. In an elevator, the combination with a constantly rotating shaft, a hoisting drum or sheave supporting an elevator car, fluid power transmission mechanism operatively connecting said shaft and drum or sheave, a variable speed electric pilot motor controlled from said car, and differential mechanism connected to run with said pilot motor and hoisting drum or sheave, and arranged to control the power transmission mechanism and thereby cause the said hoisting drum or sheave to run in synchronism with the said pilot motor.
25. In an elevator, the combination with an alternating current motor adapted to run at substantially constant speed in one direction, a hoisting drum or sheave, fluid power transmission mechanism connecting said motor and sheave, a pilot motor for controlling said power transmission mechanism, a generator driven by said alternating current motor and adapted to supply electric current to said pilot motor, and means for controlling the current to said pilot motor.
30. In an elevator, the combination with a constantly rotating shaft, a hoisting drum or sheave supporting an elevator car, fluid power transmission mechanism operatively connecting said shaft and drum or sheave, a variable speed electric pilot motor controlled from said car, and means for controlling the said power transmission mechanism by the differential action of said pilot motor and power transmission mechanism.
35. In an elevator, the combination with a constantly rotating shaft, a hoisting drum or sheave supporting an elevator car, fluid power transmission mechanism operatively connecting said shaft and drum or sheave, a variable speed electric pilot motor controlled from said car, and differential mechanism connected to run with said pilot motor and hoisting drum or sheave, and arranged to control the power transmission mechanism and thereby cause the said hoisting drum or sheave to run in synchronism with the said pilot motor.
40. In an elevator, the combination with an alternating current motor adapted to run at substantially constant speed in one direction, a hoisting drum or sheave, fluid power transmission mechanism connecting said motor and sheave, a pilot motor for controlling said power transmission mechanism, a generator driven by said alternating current motor and adapted to supply electric current to said pilot motor, and means for controlling the current to said pilot motor.
45. In an elevator, the combination with a constantly rotating shaft, a hoisting drum or sheave supporting an elevator car, fluid power transmission mechanism operatively connecting said shaft and drum or sheave, a variable speed electric pilot motor controlled from said car, and differential mechanism connected to run with said pilot motor and hoisting drum or sheave, and arranged to control the power transmission mechanism and thereby cause the said hoisting drum or sheave to run in synchronism with the said pilot motor.
50. In an elevator, the combination with an alternating current motor adapted to run at substantially constant speed in one direction, a hoisting drum or sheave, fluid power transmission mechanism connecting said motor and sheave, a pilot motor for controlling said power transmission mechanism, a generator driven by said alternating current motor and adapted to supply electric current to said pilot motor, and means for controlling the current to said pilot motor.
55. In an elevator, the combination with a constantly rotating shaft, a hoisting drum or sheave supporting an elevator car, fluid power transmission mechanism operatively connecting said shaft and drum or sheave, a variable speed electric pilot motor controlled from said car, and differential mechanism connected to run with said pilot motor and hoisting drum or sheave, and arranged to control the power transmission mechanism and thereby cause the said hoisting drum or sheave to run in synchronism with the said pilot motor.
60. In an elevator, the combination with a constantly running power motor, a hoisting drum or sheave, a fluid pressure engine operatively connected to said sheave, a pump driven by said motor and connected to said fluid pressure engine, means for controlling the output of said pump to vary the speed and power of said engine, and a rotary electric pilot motor adapted to control the operation of said pump controlling means.
65. In an elevator, the combination with a constantly running power motor, a hoisting drum or sheave, a fluid pressure engine operatively connected to said sheave, a pump driven by said motor and connected to said fluid pressure engine, and a pilot motor adapted to control the operation of said pump controlling means according to the differential speed of the said pilot motor and sheave or drum.
70. In an elevator, the combination with a constantly running power motor, a hoisting drum or sheave, a fluid pressure engine operatively connected to said sheave, a pump driven by said motor and connected to said fluid pressure engine, and a pilot motor adapted to control the operation of said pump controlling means according to the differential speed of the said pilot motor and sheave or drum.
75. In a fluid pressure power transmission a hydraulic power unit, an electric pilot motor, and means for synchronizing the said unit with the said motor.
80. In a fluid pressure power transmission, a hydraulic power unit operatively connected to a gravity load, a pilot motor, and means for synchronizing the said unit and pilot motor.
85. In a fluid pressure power transmission, a hydraulic power unit operatively connected to a gravity load, a pilot motor, and means for synchronizing the said unit with the said motor.
90. In a fluid pressure power transmission, a hydraulic power unit operatively connected to a gravity load, a pilot motor, and means for synchronizing the said unit and pilot motor.
95. In a fluid pressure power transmission, a hydraulic power unit operatively connected to a gravity load, a pilot motor, and means for synchronizing the said unit and pilot motor.
100. In a fluid pressure power transmission, a hydraulic power unit operatively connected to a gravity load, a pilot motor, and differential gearing for synchronizing the said unit and pilot motor.
105. In a fluid pressure power transmission, a hydraulic power unit operatively connected to a gravity load, a pilot motor, differential gearing for synchronizing the said unit and pilot motor, and a hand operated rheostat for controlling the speed and direction of rotation of the said pilot motor.
110. In a pump, cylinders arranged axially around a driving shaft, plungers in said cylinders constrained to move in an elliptical path, an axial duct in said shaft, means for conducting lubricant from said duct by centrifugal action to the bearing surfaces of the said pump, and means for keeping the lubricant separated from the fluid acted upon by the said plungers.
115. In testimony whereof, I have signed my name to this specification in the presence of two subscribing witnesses.
